The ornamental design for an identification transponder tag for fabric-type articles, as shown and described.

DESCRIPTION

FIG. 1 is a top plan view of an identification transponder tag for fabric-type articles showing my new design; FIG. 2 is a side elevational view thereof, with the opposite sides being a mirror image;

FIG. 3 is a bottom plan view thereof;

FIG. 4 is a top plan view of a second embodiment wherein the side elevational view appears in FIG. 2;

FIG. 5 is a bottom plan view of the second embodiment shown in FIG. 4;

FIG. 6 is a top plan view of a third embodiment wherein the side elevational view appears in FIG. 2; and,

FIG. 7 is a bottom plan view of the third embodiment shown in FIG. 6.

FIG. 6

FIG. 7

FIG. 4

FIG. 5

FIG. 1

FIG. 2

FIG. 3
